DESIGN FOR A LINK CHAIN FOR A BRACELET OR SIMILAR ARTICLE

Paul Bardach, Providence, R. I.

Application June 19, 1947, Serial No. 139,801

Term of patent 3½ years

(Cl. D45—16)

To all whom it may concern:

Be it known that I, Paul Bardach, a citizen of the United States, residing at Providence, in the county of Providence and State of Rhode Island, have invented a new, original and ornamental Design for a Link Chain for a Bracelet or Similar Article, of which the following is a specification, reference being had to the accompanying drawing, constituting a part hereof.

Fig. 1 is a top plan view of a link chain for a bracelet or similar article showing my novel design;

Fig. 2 is a bottom plan view; and
Fig. 3 is as side view of one link.

I claim:

The ornamental design for a link chain for a bracelet or similar article, substantially as shown.

PAUL BARDACH.
